UNITED STATES PATENT OFFICE.

GEORGE F. EBERHARD, OF TRENTON, NEW JERSEY, ASSIGNOR TO ROBT. H. INGERSOLL
& BRO., A JOINT-STOCK ASSOCIATION OF NEW YORK.

WINDING-CLUTCH FOR WATCHES.

1,144,827.

Specification of Letters Patent. Patented June 29, 1915.

Application filed January 2, 1914, Serial No. 809,965. Renewed May 8, 1915. Serial No. 26,900.

To all whom it may concern:

Be it known that I, GEORGE F. EBERHARD, citizen of the United States, residing at Trenton, New Jersey, have invented certain new and useful Improvements in Winding-Clutches for Watches, of which the following is a specification.

It is the object of my invention to provide a winding clutch for watches and like instruments which can be accurately produced at small expense.

In carrying out my invention I utilize a swaging action to provide the clutch and crown teeth, instead of cutting them, and in order to successfully employ a swaging action I form the clutch in sections, so that the two ends which are to be toothed can be subjected to the swaging operations without liability of distorting the piece operated on. The swaged teeth are of advantage over the cut teeth because when a cutting operation is employed burs are left on the teeth which must be removed, entailing an additional operation. Then again cut teeth are irregular, due to the wearing of the cutter. Swaged teeth are uniform, free from burs, can be rapidly made and are superior in use to cut teeth because of the polishing and consolidating effect on the metal of the swaging tool.

The invention is illustrated in the accompanying drawings in which,

Figure 1 is a sectional view of a winding clutch as heretofore made; Fig. 1^a is a plan view; Figs. 2 and 2^a are respectively a sectional view and a plan view of one form of my improved clutch; Fig. 2^b is a view showing the parts of Fig. 2 separated; Figs. 3 and 3^a are respectively a sectional view and a plan view of another form of winding clutch composed of three pieces; Fig. 3^b is a view of the parts of Fig. 3 separated from each other; Fig. 4 is a sectional view, and Fig. 4^a is a plan view of another form of my invention composed of two pieces, and Fig. 4^b shows these pieces in side elevation, separate from each other; Fig. 5 is a sectional view of another form of my invention consisting of three pieces; Fig. 5^a is a plan view of Fig. 5, and Fig. 5^b shows the parts of Fig. 5 in side elevation and separated from each other.

Referring to Fig. 1, the old form of winding clutch, this is produced all in one piece

with the toothed ends, the central circumferential groove and with an axial opening rectangular in cross section, and in producing this clutch many operations are necessary, approximately eighteen in number.

In producing my clutch according to the form shown in Figs. 2, 2^a and 2^b, I make it in separate pieces, these pieces having the clutch and crown teeth formed therein at 6, 6^a, and one of the pieces having a flange 7 and a socket 8 to receive a reduced cylindrical portion 9 on the other piece, this other piece being shouldered at 10 to make a close joint with the surface of the flange 9. Each of these pieces is provided with an axial opening rectangular in cross section, as shown in Fig. 2^a. In forming the two pieces they are produced in an automatic machine in the general form illustrated and then each piece is subjected to a swaging in swaging dies to produce the teeth. The flange 7 is intended to afford means for engagement with the operating lever which shifts the clutch.

In Fig. 3 the clutch is formed of three pieces, the center piece having a flange 7' and reduced cylindrical ends or projections 11 to fit within sockets formed on the adjacent ends of the end portions 12 and 13 which carry the teeth. The center piece is provided with a cylindrical opening therethrough while the two end pieces are provided with openings rectangular in cross section to fit the winding stem.

In Fig. 4, instead of providing a flange for engagement with the operating lever a circumferential groove 7'' is provided by forming and uniting the pieces in the relation shown, one piece having a reduced extension 14 fitting in a socket 15 of the other piece and extending to near the point where the teeth are formed. Both of these pieces have an axial opening rectangular in cross section, and the teeth may be swaged on both of these pieces and the square opening may be punched through the member 16.

Fig. 5 shows the clutch made up of a cylindrical center member 17, and the two end members 18, 19, of larger external diameter. Each of these members is provided with a cylindrical recess or socket receiving the end of the cylindrical center. These ends bear on the shoulders or ribs 20 formed in the pieces 18 and 19. When assembled, as

shown in Fig. 5, the clutch piece has the circumferential groove left or formed therein for the operating or controlling lever to engage with.

5 In making the end pieces the teeth are swaged in and the square holes are punched, the swaging being done first and then the punching is performed. The formation of the teeth first enables the piece to be positioned and held for the punching of the 10 square hole.

By making the clutch in parts, as described the number of operations necessary for its formation are greatly reduced, as 15 will be obvious from the fact that swaging and punching operations may be largely employed.

The circumferential groove in some of the forms, like the flange in other forms, constitutes the means for engaging with the operating or shifting lever or other member. 20

In placing the parts together the rectangular openings which are to engage the winding stem are matched or registered in staking or driving them together. The parts 25 are united by a driving fit no special means of attachment being necessary, this being true of all forms.

Reverting to Fig. 1, swaging operations, 30 if exercised upon a clutch formed in one piece, would distort the same and therefore in the manufacture of such one piece clutches recourse has been had heretofore to a milling or cutting action in forming the 35 teeth, resulting in the formation of burs and requiring re-turning and wire brushing to true up the piece and remove the burs.

I claim:—

1. A clutch for watches composed of 40 separate parts including two ends and intermediate means for engagement with the op-

erating member, said clutch having terminal swaged teeth, substantially as described.

2. A winding clutch for watches composed of separate parts including two ends 45 having teeth swaged on the end faces thereof and intermediate means for engagement with the operating member, substantially as described.

3. A winding clutch for watches composed of separate pieces including two ends 50 having teeth swaged on the end faces thereof, said pieces having also a socket and reduced connection between said pieces, substantially as described.

4. A winding clutch for watches composed of separate pieces including two ends 55 with swaged teeth thereon with a socket and reduced connection between, the said pieces being spaced apart by said reduced connection to provide a circumferential 60 groove, substantially as described.

5. A winding clutch for watches composed of two end portions similarly socketed and having swaged teeth, and an 65 intermediate portion fitting within the sockets of the end portions, all of said parts having interior openings for receiving the winding stem.

6. A winding clutch for watches composed of two end portions having swaged 70 teeth and provided with similar sockets, and a sleeve connecting member fitting said sockets and spacing the members apart to form a groove for receiving an operating 75 member, substantially as described.

In testimony whereof, I affix my signature in presence of two witnesses.

GEO. F. EBERHARD.
